CARD HOLDER

Mary Frances Lee, Brooklyn, N. Y.

Application October 11, 1955, Serial No. 38,322

Term of patent 14 years

(Cl. D34—13)

Fig. 1.

Fig. 2.

Fig. 3.

I claim:

The ornamental design for a cardholder, substantially as shown.
